UNITED STATES PATENT OFFICE.

CHARLES W. MESSNER, OF PHILADELPHIA, PENNSYLVANIA.

GROUND-WIRE ATTACHMENT.

No. 920,364.

Specification of Letters Patent.

Patented May 4, 1909.

Application filed February 26, 1908. Serial No. 417,970.

To all whom it may concern:

Be it known that I, CHARLES W. MESSNER, a citizen of the United States, residing at Philadelphia, in the county of Philadelphia and State of Pennsylvania, have invented 5 a certain new and useful Ground-Wire Attachment, of which the following is a specification.

This invention relates to attachments for 10 forming ground connections for electric circuits; and has for its principal object to provide a simple, durable, efficient and comparatively inexpensive form of device that may be readily connected to or disconnected from 15 conducting objects as water or gas pipes or conduits of various sizes; and a further object is to provide an attachment constructed in a manner hereinafter referred to as adapted to receive the bare end of a ground wire so that 20 a soldered contact may be readily and conveniently made around all parts of the wire; and a still further object is to provide a one piece device wherein any leaking current 25 will pass in an uninterrupted manner through the same to the conducting object.

Other objects of the invention will appear hereinafter.

The invention consists of the improvements hereinafter described and finally 30 claimed.

The nature, characteristic features and scope of the invention will be more fully understood from the following description taken in connection with the accompanying drawings forming part hereof and in which:—

Figure 1, is a plan view of a metallic strip duly stamped from a blank and adapted to be formed in accordance with the invention. Fig. 2, is a view in central section of the same. 40 Fig. 3, is a view in elevation illustrating the strip when properly bent into the form of an attachment embodying the invention. Fig. 4, is a top or plan view thereof. Fig. 5, is a similar view illustrating the manner of forming connection with a conducting object, and Fig. 6, is a view in cross section, drawn to an enlarged scale, and illustrating a similar connection.

In carrying out the manufacture of the attachment of the invention it has been found 50 that good results may be obtained by stamping from comparatively thin metallic blanks of copper, brass or other good conductive material, a one piece elongated strip 1, see 55 Figs. 1 and 2, having at one of its shorter ends a generally V-shaped, centrally ar-

ranged, comparatively large notch 2, and upon each side thereof smaller notches 3, of the same general shape as the first mentioned notch. The corners of the opposite end of the strip 1, are cut off as at 4, and at its approximate center has stamped therefrom oppositely disposed tongues 5. Apertures suitable for the passage therethrough of clamping bolts, hereinafter referred to are drilled 60 in the strip 1, as at 6. The above described strip is then bent to conform to the conducting object to which it is to be applied, see Figs. 3 and 4, and in this respect it may be remarked that a generally circular band 7, is 65 provided in the present instance and is adapted for application to a pipe 14, the said band terminating in flat outward extensions or ears 8 and 9, of which the ear 8, is slightly longer than the ear 9. As is clearly illustrated by this formation the openings 6, are arranged in alinement, one above the other, as are the lips 5, it being understood that when the strip 1, is bent into proper form these lips 5, project within the band 7, of the 70 attachment and serve to scrape the pipe 14, when the attachment is clamped and bolted thereto, thus insuring a bright, clean and permanent contact. The outer end or notched portion of the ear 8, is rolled or turned over 75 as it were to form a tubular socket 10, for the reception of the bare end of a ground wire 11, the socket being so arranged that the wire within the socket is held parallel with the pipe 14. In this connection the V-shaped 80 notches afford convenient means for soldering the ground wire within the tubular socket 10. The method of so soldering the wire consists of first heating, preferably by means of a soldering iron, the wire within the socket 85 and then applying a flux and, while the wire is still hot applying solder to the notched portion of the socket which by reason of the said notches, freely flows within the socket and around the wire within the socket thus making 90 a soldered contact that is neat in appearance and effective in operation. In this connection it may be remarked that the larger sized notch is used particularly for the insertion of solder and the smaller sized notches 95 provide means whereby the workman may readily ascertain whether or not the solder so applied has been caused to flow throughout the entire length of the socket. It is important to have the solder flow throughout 100 the entire length of the socket in order to provide a good connection.

The attachment may be clamped to a pipe or conduit by means of the clamping bolt 12, that passes through the apertures 6, in the ears or extensions 8 and 9, and is provided with a nut 13, in which the bolt is turned to draw the ears 8 and 9, together to closely embrace the pipe 14, see Figs. 5 and 6, and the attachment being of one piece and comparatively thin metal a more or less resilient device is provided which obviously is advantageous in securing the same to a pipe or conduit. Also being a one piece device, any current that passes to the pipe or conduit, does so directly without interruption such as would be caused by two parts overlapping or by passing through binding screws or bolts and nuts.

What I claim is:

1. An attachment of the class recited comprising a member terminating in a substantially flat extension, the outer end of which is formed into a sleeve, having a longitudinally notched edge.
2. An attachment of the class recited comprising a member terminating in a substantially flat extension, the outer end of which is formed into a sleeve, the longitudinal edge of which is notched, said edge being arranged adjacent to said extension.
3. An attachment of the class recited comprising a member terminating in a substantially flat extension, the outer end of which is formed into a sleeve, having a series of solder receiving openings.

4. An attachment of the class recited comprising a member terminating in a substantially flat extension, the outer end of which is formed into a sleeve, having a comparatively large centrally disposed solder receiving opening and being provided upon opposite sides of said opening with comparatively small openings.

5. An attachment of the class recited comprising a member terminating in a substantially flat extension, the outer end of which is formed into a sleeve, having substantially V-shaped solder receiving openings.

6. An attachment of the class recited comprising a member terminating in a substantially flat extension, the outer end of which is formed into a sleeve, having a comparatively large centrally located V-shaped solder receiving opening, and having arranged upon opposite sides of said opening comparatively small V-shaped openings.

7. An attachment of the class recited comprising a general sleeve-like member constituting a wire receiving socket, said socket being provided with a series of openings for the flowing of solder throughout the entire length of the socket.

In testimony whereof I have signed this specification.

CHARLES W. MESSNER.
